(No Model.)

H. RUDDELL.
SHUTTER WORKER.

No. 350,896.

Patented Oct. 12, 1886.

UNITED STATES PATENT OFFICE.

HIRAM RUDDELL, OF ATLANTA, GEORGIA.

SHUTTER-WORKER.

SPECIFICATION forming part of Letters Patent No. 350,896, dated October 12, 1886.

Application filed August 9, 1884. Serial No. 140,110. (No model.)

To all whom it may concern:

Be it known that I, HIRAM RUDDELL, a citizen of the United States of America, residing at Atlanta, in the county of Fulton and State of Georgia, have invented certain new and useful Improvements in Blind-Operators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improved device for opening, closing, fastening, or holding shutters, the same being operated from the interior of the building.

In the accompanying drawings, which illustrate my invention, Figure 1 is a perspective view, Fig. 2 a sectional view, and Fig. 3 a modification.

20 A represents the window-frame, to which the shutter B is hinged, said shutter abutting at its lower end against a sub-sill, C, attached to the lower portion of the window-frame. The sub-sill is provided at a point near the side of the window-frame with a recess, a, one side of which is substantially straight, 30 while the opposite side is curved, as shown at a', and provided at this side with a spring, b.

Attached to the shutter B at a point opposite the recess a, when the shutter is closed, is a bracket, c, having an upward extension, c', and a horizontally-projecting portion, c'', to which one of the links of a flexible chain is attached. A series of links, d, are attached to the bracket and an end link, d', which is pivoted to an operating bar or handle, D. The 35 links d constitute together a flat flexible connection. The inner side of the links are cut away or beveled, so as to allow the chain to bend, so as to form the segment of a circle, while the outer portion of the links are at 40 right angles with their side, the joints abutting against each other, so as to prevent the same being turned in an opposite direction, or more than straight. Pintles e connect each link of the chain with the next. The last 45 link, d', is provided with an eye, f, through which passes a horizontal pintle, which connects the same with an operating-handle, D, which operating-handle is provided at suitable intervals with notches or recesses g g,

which engage with a suitable rigid projection, 55 and thus holds the blind in a fixed position.

On the inner side of the rail C, opposite the opening a, is attached a suitable slotted plate, h, through which passes the chain and bar D, the spring hereinbefore described 60 pressing upon said bar throws the notches therein in engagement with one side of the plate, thus making the blind secure in any desired position as opened, closed, or bowed. A pin, G, is attached to the window-easing, 65 and projects upwardly therefrom, and is adapted to engage with the notches of the handle-bar D, to hold the blind in a closed position, as shown in Fig. 2, and for this purpose the handle-bar is hinged to the link d' by 70 a horizontal pintle.

From the foregoing it will be seen that in order to open the blind, it is necessary, first, to raise the handle-bar D, so as to bring the same out of engagement with the pin G, the 75 handle-bar is then swung around, so as to be at substantially right angles with the window-frame, and by pushing the same outwardly the blind is swung open, the links becoming substantially rigid as bent upon each 80 other, owing to the bevel on their inner sides. When the blind is opened or partially opened, it may be secured in such position by the handle-bar coming in contact with the plate h, the notches in said handle-bar being thrown 85 or pressed against the plate by the spring.

Having thus described my invention, what I claim as new, and desire to secure by Letters Patent, is—

The combination, in a shutter-worker, of a 90 bar, D, having a series of notches, a series of links pivotally connected by vertical pins, each link being provided at each end with a beveled shoulder adapted to form a bearing for the like shoulders of the adjacent links, 95 so that said links will present a rigid connection between the bar D and shutter, the end link of the series being adapted for attachment to the shutter, a projection engaging said bar D, and a horizontal pivot connecting one 100 of the links, d', with the bar D, substantially as set forth.

In testimony whereof I affix my signature in presence of two witnesses.

HIRAM RUDDELL.

Witnesses:

S. H. LANDRUM,
G. W. COLLIER.
